T. F. WARE,
DEMOUNTABLE RIM STRUCTURE,
APPLICATION FILED JULY 7, 1919.

1,333,518.

Patented Mar. 9, 1920.

UNITED STATES PATENT OFFICE.

THOMAS F. WARE, OF SALT LAKE CITY, UTAH.

DEMOUNTABLE-RIM STRUCTURE.

1,333,518.

Specification of Letters Patent.

Patented Mar. 9, 1920.

Application filed July 7, 1919. Serial No. 309,247.

To all whom it may concern:

Be it known that I, THOMAS F. WARE, a citizen of the United States, residing at Salt Lake City, in the county of Salt Lake 5 and State of Utah, have invented certain new and useful Improvements in Demountable-Rim Structures; and I do declare the following to be a full, clear, and exact description of the invention, such as will enable others skilled in the art to which it 10 appertains to make and use the same.

This invention relates to automobile rims, and more specifically to an improved lock for demountable rims.

15 One object of this invention is to provide an improved demountable rim lock that is exceedingly effective, strong, durable, convenient and comparatively inexpensive.

Other objects and advantages may become 20 apparent to persons who read the following details of description in connection with the accompanying drawings, in which:—

Figure 1 is an elevation illustrating a wheel embodying the present invention.

25 Fig. 2 is an enlarged radial sectional view, the section being taken along the line 2—2 of Fig. 1.

Fig. 3 is an enlarged radial sectional view, the section being taken along the line 3—3 30 of Fig. 1, the felly being omitted.

Fig. 4 is a fragmental detail view showing one of the axially and circumferentially extending grooves of the outer rim.

Fig. 5 is a perspective view of the improved key which is shown in section in 35 Fig. 2.

Referring to these drawings in detail, in which similar reference characters correspond with similar parts throughout the several views,—

The device consists of an outer rim 6, an inner rim 7, a locking key 8, an internally and externally threaded tubular element 9, a thumb-screw 10 and a plurality of studs 45 11. Any appropriate number of the studs 11 may be provided, and a corresponding number of axially and circumferentially extending slots 12 is provided, it being understood that each of the studs 11 is normally seated in a corresponding one of the grooves 12, thereby preventing axial relative movement of the inner and outer rims when in their normal relation to one another as shown in the drawings. The studs 11 are 50

55 preferably formed on the ends of screws 13 which are seated and countersunk in the

inner rim 7, and the felly 14, being seated against the heads of the screws 13, prevents their displacement.

In order that the inner and outer rims 60 may be effectually prevented from moving circumferentially with relation to one another, a key-seat 15 is provided in the outer rim, and a corresponding key seat 16 is provided in the inner rim. The key 8 is sufficiently thick and wide to fill both of the key-seats 15 and 16 and the walls of these key-seats are in contact with the edges of the key 8, and therefore, the inner and outer rims are locked against circumferential relative movement. The key 8 is formed with a depression 17 which receives one end of the screw 10, the other end of the screw being 65 preferably formed with a manipulative element 18. The screw 10 is threaded within 70 the tubular member 9, and the latter is secured to the rim 7 and felly 14 by means of an enlarged or flared end portion 19 and a threaded end portion 20, a nut 21 being threaded on the portion 20. The key 8 is 75 preferably provided with a flange 22 which is engageable with a screw-driver or other appropriate tool for removing the key 8 from the seats 15 and 16 when the screw 10 is disengaged with the depression 17, 80 and the front end of the key is substantially 85 wedge-shaped, as indicated at 23, so that it may be forced into the seats 15 and 16 in the event these seats are not in perfect registration when the key is started. By 90 thus forcing the key into the seats 15 and 16, the studs 11 are forced into their normal positions in the grooves 12.

In removing the inner rim from the outer rim, the key 10 is first unscrewed sufficiently 95 to clear the depression 17, the key 8 is then removed, the inner and outer rims are moved circumferentially with relation to one another until the studs 11 register with the axial or axially parallel portions of the slots 100 12, and the outer rim may now be withdrawn by moving it axially with relation to the inner rim. In replacing the outer rim, the foregoing operation is of course reversed.

Although only one of the keys and a corresponding one of the screws 10 is here shown and described, it is obvious that any appropriate number of these elements may be employed in the construction of a wheel.

It is not intended to limit this invention 110 to the exact details of construction and arrangement here described and illustrated,

but appropriate changes may be made within the scope of the inventive ideas, as here involved.

What I claim as my invention is:—

- 5 1. A demountable rim structure comprising an outer rim formed with grooves each extending axially and circumferentially, an inner rim having studs normally seated in the circumferential parts of said grooves, a key normally seated between said outer and inner rims and being effective to prevent circumferential relative movement of the outer and inner rims, said key having a depression therein, a felly, a tubular member extending through the felly and inner rim and being secured to the latter, a nut threaded on said tubular member and seated on said felly, and a screw normally extending through said felly and inner rim and into said depression of said key.
- 10 15 2. A demountable rim structure comprising

ing an outer rim formed with grooves each extending axially and circumferentially, an inner rim having studs normally seated in the circumferential parts of said grooves, a key normally seated between said outer and inner rims and being effective to prevent circumferential relative movement of the outer and inner rims, said key having a depression therein, a felly, a tubular member extending through the felly and inner rim and being secured to the latter, a nut threaded on said tubular member and seated on said felly, and a screw normally extending through said felly and inner rim and into said depression of said key.

In testimony whereof I have hereunto set my hand.

THOMAS F. WARE.
